Motors Corporation, Detroit, Mich., a corporation of
Delaware

Application June 17, 1958, Serial No. 51,412

Term of patent 7 years

(Cl. D14—3)

Figure 1 is a front elevational view of an automobile showing my new design, the portion of the automobile not shown being conventional;

Figure 2 is an enlarged view of a portion of Figure 1;

Figure 3 is a top plan view;

Figure 4 is a sectional view taken on the plane indicated by line 4—4 of Figure 2;

Figure 5 is an enlarged sectional view taken along the plane indicated by line 5—5 of Figure 4;

Figure 6 is an enlarged sectional view taken along the plane indicated by line 6—6 of Figure 2; and

Figure 7 is a perspective view of a portion of Figure 1.

The dominant features of my new design reside in the full line portions of the drawings.

I claim:

The ornamental design for an automobile, substantially as shown and described.
